US00D720634S

(12) **United States Design Patent**
Dempsey et al.

(10) **Patent No.:** **US D720,634 S**
(45) **Date of Patent:** **** Jan. 6, 2015**

(54) **PERSONAL NAVIGATION DEVICE**

(71) **Applicant:** **TomTom International BV**, Amsterdam (NL)

(72) **Inventors:** **Mark Lee Dempsey**, Beckenham (GB); **Daniel Browning**, Amsterdam (GB); **Kyle Loughlin**, London (GB); **Tim Williamson**, London (GB); **Stephen de Saulles**, London (GB); **Marcus Hoggarth**, London (GB)

(73) **Assignee:** **TomTom International B.V.**, Amsterdam (NL)

(**) **Term:** **14 Years**

(21) **Appl. No.:** **29/468,907**

(22) **Filed:** **Oct. 4, 2013**

(30) **Foreign Application Priority Data**

Apr. 5, 2013 (EM) 002215053-0002

(51) **LOC (10) Cl.** **10-04**

Primary Examiner — Antoine D Davis

(57) **CLAIM**

The ornamental design for a personal navigation device, as shown and described.

DESCRIPTION

FIG. 1 is a perspective view showing the front and upper surface of the device.

FIG. 2 is a rear view of the device.

FIG. 3 is a front view of the device.

FIG. 4 is a bottom view of the device.

FIG. 5 is a top view of the device; and,

FIGS. 6 and 7 are opposing side views of the device.

Portions of FIG. 4 are shown in dashed lines for illustrative purposes only and form no part of the claimed design.

1 Claim, 3 Drawing Sheets
